CLAIM

The ornamental design for a transparent thermoformed container with an opaque yellow rack insert, as shown and described.

DESCRIPTION

FIG. 1 is a front perspective view of a transparent thermoformed container showing the new design with an opaque yellow rack insert;

FIG. 2 is a front side elevation view of the transparent thermoformed container with an opaque yellow rack insert; FIG. 3 is a rear side elevation view of the transparent thermoformed container with an opaque yellow rack insert; FIG. 4 is a left side elevation view of the transparent thermoformed container with an opaque yellow rack insert; FIG. 5 is a right side elevation view of the transparent thermoformed container with an opaque yellow rack insert; FIG. 6 is a top plan view of the transparent thermoformed container with an opaque yellow rack insert;

FIG. 7 is a bottom plan view of the transparent thermoformed container with an opaque yellow rack insert;

FIG. 8 is a front perspective view of the transparent thermoformed container with an opaque yellow rack insert showing a front latch in an unlatched position; and,

FIG. 9 is a front perspective view of the transparent thermoformed container with an opaque yellow rack insert showing the lid open to expose the opaque yellow rack insert.

The broken lines in the drawings are included for the purpose of illustrating surface features of the transparent thermoformed container with an opaque yellow rack insert that form no part of the claimed design. The rack insert lined for the color yellow, namely Pantone 7403C.
